CLAIM

The ornamental design for a pipette tip for a laboratory instrument, as shown and described.

DESCRIPTION

FIG. 1 is a perspective view of a pipette tip for a laboratory instrument showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a cross sectional view taken along line 8-8 shown in FIG. 6.
